GAME BOARD OR THE LIKE

Ann G. McNaughton, 11 Orchard Drive, Monroe, N.Y.

Filed Dec. 1, 1964, Ser. No. 82,859

Term of patent 14 years

(Cl. D34—5)

The figure is a top plan view of a game board, showing my new design.

The board is of conventional thickness. Furthermore, the dominant features of my design reside in the portions shown in full line.

I claim:

The ornamental design for a game board or the like, substantially as shown and described.
